US0D1051368S

(12) **United States Design Patent** (10) **Patent No.:** **US D1,051,368 S**
(45) **Date of Patent:** **** Nov. 12, 2024**

(54) **RECEPTACLE**

(71) Applicant: **GEN-PROBE INCORPORATED**, San Diego, CA (US)

(72) Inventors: **David A. Buse**, San Diego, CA (US); **Byron J. Knight**, San Diego, CA (US)

(73) Assignee: **GEN-PROBE INCORPORATED**, San Diego, CA (US)

(**) Term: **15 Years**

(21) Appl. No.: **29/794,587**

(22) Filed: **Jun. 14, 2021**

Related U.S. Application Data

(63) Continuation of application No. 16/560,476, filed on Sep. 4, 2019, now Pat. No. 11,035,613, which is a continuation of application No. 15/745,834, filed as application No. PCT/US2016/045166 on Aug. 2, 2016, now Pat. No. 10,443,935.
